COLLAPSIBLE RECEPTACLE

Filed July 14, 1928

INVENTOR.

George B. Ingersoll

UNITED STATES PATENT OFFICE

GEORGE B. INGERSOLL, OF DEARBORN, MICHIGAN, ASSIGNOR TO ELLA I. INGERSOLL,
OF DEARBORN, MICHIGAN

COLLAPSIBLE RECEPTACLE

Application filed July 14, 1928. Serial No. 292,897.

My invention relates to improvements in collapsible receptacles having means for controlling the flow of contents therefrom; and the objects of my improvement are, first, to provide a dispensing device having no removable or exteriorly moving parts; second, to provide a device having an internal valve manually operable from the outside of its collapsible member; third, to provide a device having a manually operated valve located wholly within itself and with no exterior portions; fourth, to provide a device having sanitary dispensing features; fifth, to provide a device having a valve operable by pressure upon a comparatively small portion of its collapsible surface; and sixth, to provide a dispensing device having a manual control over its inherent internal pressure.

I attain these objects by the mechanism illustrated in accompany drawing, in which—

Figure 1 is an elevation of the complete receptacle ready for use; Fig. 2, a side elevation of the complete receptacle ready for use; Fig. 3, an end view of the receptacle; Fig. 4, a sectional view on the line 4—4, Fig. 3; Fig. 5, a sectional view on the line 5—5, Fig. 4; Fig. 6, a side view of the slidable member; Fig. 7, an elevation of the slidable member; Fig. 8, an end view of the guide member; Fig. 9, a side elevation of the guide member; Fig. 10, a side elevation of the guide member; and Fig. 11, a view displaying the receptacle in operation.

Similar numerals refer to similar parts throughout the several views.

The body 1 of the receptacle is made of flexible material as is usual in ordinary commercial collapsible devices and is readily compressible. The head 2 is made of sufficiently stiff metal to form a housing for valve parts and an extension for use as a nozzle 3. The body 1 is suitably attached or formed to the head 2 and has its other end 4 flattened and closed by rolling in the usual manner, according to the amount of contents in the receptacle. The slidable member 5 has an opening 6 which is adapted to register with the discharge opening 7 in the end of the nozzle 3. The slidable member 5 is retained and guided by the fixed

member 8 which may be pressed into the hollow nozzle 3 thus forming a guide space 9 between the end walls of the nozzle 3 and the fixed member 8. The fixed member 8 is also provided with an opening 10 which registers with the opening 6 in the slidable member 5 when the slidable member 5 is moved to permit the discharge of the contents of the receptacle. The fixed member 8 may be provided with an indented surface 11 for retaining one end of the spring 12 while a similar indentation 13 may be provided in the slidable member 5 for retaining the other end of the spring 12. A similar indentation 14 may be provided in the wall of the nozzle 3 for engaging the indentation 11 in the fixed member 8, thus retaining the fixed member 8 in the nozzle 3. The fixed member 8 may also be provided with ribs 15 for guiding the slid-
able member 5. The slidable member 5 has an extension 16 having a surface 17 which engages the collapsible body 1 sufficiently to slightly bulge the body 1 as at 18. The fixed member 8 may be made to fit within the nozzle for more than half the inside diameter of the nozzle thus preventing the fixed member from cocking in the nozzle when pressure is applied to the slidable member 5. The slidable member 5 may be also formed to fit the inside diameter of the nozzle as at 19. In Fig. 11, the receptacle is shown depositing its contents on the tooth brush 20.

The body 1 is rolled up at its end 4 until pressure is built up in the receptacle or a slight pressure may be exerted on the rear end of the body 1 by the hand in which it is grasped. Then a slight pressure on the bulge 18 by a finger 21 will cause the slidable member 5 to move to the position, as shown by dotted lines 22, when the openings 10, 6, and 7 will register allowing the contents to flow out as shown in Fig. 11. The end 23 may be made of sufficient length to contact with the inside wall of the nozzle 3 when the openings 10, 6, and 7 are registered, thus forming a stop for the slidable member 5 when operated by the finger 21. As soon as a sufficient amount of the contents has left the receptacle, the release of the finger

pressure will allow the spring 12 to force the slidable member 5 back to its original position when it will again bulge the body 1 as at 18. The slidable member 5 being located close to the front end wall of the tube 1 will allow for the use of practically all of the contents of the receptacle. It is to be noted that the spring 12 will have to displace but a small amount of the contents of the 10 receptacle when it returns the slidable member 5 to its original position.

It is also to be noted that my device does away with the removal and frequent loss of the usual threaded cap on the nozzle of the 15 prevalent type of collapsible receptacle. It is this removal and loss which causes the ordinary collapsible tube to become the most unsanitary thing in household use through the collection of unused contents lodging on 20 the nozzle, this unused portion making a splendid lodging for all kinds of germs.

The presence of such germ infected accumulation on such things as tooth and 25 toilet articles constitutes a grave danger to health. In my device no part of the hands need touch the nozzle with the result that no danger from germs attends the use of my device even though some is used by different parties. If any of the contents lodge around 30 the opening in the nozzle, when the finger pressure is removed from the spot 18, the entire nozzle end of the tube may be held under the faucet, the running water immediately removing all particles of the contents. 35

I claim:

1. The combination of a receptacle having 40 a collapsible wall and a nozzle formed with an opening, and a slidable member formed with an opening for registry with the opening in the nozzle of said receptacle, said slid- 45 able member having a button portion contacting with a remotely located portion of the inside surface of the collapsible wall of said receptacle, said slidable member being wholly enclosed within said receptacle.

2. The combination of a receptacle having 50 a collapsible wall and a nozzle formed with an end opening, and a member slidably operated under manually exerted pressure, said member being contained within said receptacle and having contact with a portion of the collapsible wall remotely located from the nozzle of said receptacle, said member there- 55 by controlling the flow of contents from said receptacle.

3. The combination of a receptacle having 60 a collapsible wall and a nozzle formed with an end opening, a slidable member for controlling the flow of contents from said receptacle, said slidable member contacting with the collapsible wall of said receptacle, and means for returning said slidable member to a position whereby the contents of said receptacle are prevented from flowing there- 65 from, said means lying transversely within

said nozzle and parallel with said slidable member.

4. In a collapsible receptacle having a nozzle with an opening, a member mounted within the nozzle of the collapsible receptacle, a 70 slidable member mounted between the nozzle of the collapsible receptacle and said member within the nozzle, said slidable member having a surface in contact with the collapsible wall of the receptacle, and means for returning said slidable member to a position whereby the contents of the collapsible receptacle are prevented from escaping therefrom. 75

5. In a receptacle, the combination of enclosing walls provided with a single aperture 80 therein, said enclosing walls being further provided with a designated portion for the application of manual pressure, and means for opening and closing the single aperture of said enclosing walls, said means engaging the inside surface of the enclosing walls adjacent said designated portion for the application of manual pressure. 85

6. In a receptacle, the combination of a 90 collapsible member having a nozzle provided with an opening, a movable member for covering and uncovering the opening in the nozzle of said collapsible member, said movable member having an end contacting with and displacing a portion of the wall of said collapsible member, a portion of said movable member being contained between the walls of said collapsible receptacle, and automatic means for operating said movable member to close the opening of the nozzle of said collapsible receptacle, said automatic means further operating said movable member to cause said portion of the wall of said collapsible receptacle to return to a non-collapsed position. 100

7. In a collapsible receptacle having a discharge orifice, valve means for controlling the flow of the contents therefrom through said orifice, said valve means having no portions extending through any portions of said receptacle, said valve means being provided with a button portion to permit said valve means to be manually moved in said receptacle, said button portion of said valve means engaging the inside surface of the wall portions of said receptacle, said button portion of said valve means further exerting a pressure against the wall portion of said receptacle to cause a collapsed portion of said receptacle to assume a non-collapsed position. 110

8. In a receptacle provided with a collapsible wall together with a discharge opening, valve means for opening and closing the discharge opening of said receptacle, said valve means being provided with a portion adapted to engage the collapsible wall of said receptacle, said portion being connected with said valve means and adapted to move therewith, said portion thereby moving a portion of the collapsible wall of said receptacle 125 130

from a collapsed position to a non-collapsed position when said valve means is being operated.

9. The combination of a receptacle having
5 a collapsible wall, a valve member having a
button portion covered by the collapsible
wall of said receptacle, said button portion
engaging the collapsible wall portion of said
receptacle to permit manual operation of said
10 valve member from the outside surface of
the collapsible wall, and means for actuating
said valve member against the collapsible
wall of said receptacle.

10. The combination of a receptacle having
15 a collapsible wall together with an apertured
nozzle, a valve member for opening and clos-
ing the apertured nozzle of said receptacle,
said valve member having a portion extend-
ing beyond the apertured nozzle into the in-
20 terior of said receptacle, said portion having
a surface engaging an inside surface of the
collapsible wall of said receptacle, and means
for moving said valve member to open and
close the apertured nozzle of said receptacle,
25 said means further actuating said valve mem-
ber to move the collapsible wall of the recep-
tacle.
